PRESSING OR IRONING MACHINE

Gerrit Hendrikus Haverkate, Almelo, Netherlands

Application August 10, 1949, Serial No. 109,437
In the Netherlands December 31, 1947

5 Claims. (Cl. 38—30)

1

The present invention relates to a pressing or ironing machine comprising a vertically movable pressing iron adapted to be displaced by hand in horizontal direction. In machines of this kind, the downward movement of the iron for producing the pressing or ironing pressure, hitherto, is effected by means of a foot operated pedal, comprising a return spring.

The present invention has for its object to provide an improved pressing or ironing machine of the kind referred to and consists therein, that the pressing or ironing pressure is supplied by a pressure fluid under the control of a control member moving with the iron and arranged immediately adjacent the grip thereof. In this connection it is observed that for operating the movable flap of the known apparatus for pressing garments, the use of air under pressure is known per se.

The application of the present invention provides for a very lightly operating machine, adapted to be controlled in an extremely easy and quick manner, seeing that the force to be exerted by the operator is exclusively limited to the horizontal displacement of the iron after the pressure fluid has been cut off and to the control of the pressure fluid supply, which may be effected with the same hand which manipulates the iron.

Machines of this type are commonly provided with means for steaming the work to be pressed through the iron and drawing off the steam from the work through the pressing plate, the supply of the steam being controlled by a handle arranged adjacent the grip of the iron.

In the application of the present invention to a machine of this kind, according to a further characteristic feature of the invention, the element for controlling the pressure fluid is combined with the element for controlling the steam supply, into a single control unit, in such a manner that the supply of the pressure fluid and that of the steam are simultaneously opened and cut off by a single manipulation.

For controlling the pressure fluid supply, in accordance with the present invention, the control element i. e. in the above mentioned case, the handle performing the dual function may be connected by means of a Bowden wire to one arm of a lever, of which the other arm under the influence of a spring, exerts on the pressure fluid supply valve, a force tending to open said valve against the fluid pressure, said spring force being just insufficient to overcome the fluid pressure on the valve, in such a manner that

2

only this difference is to be supplied by hand, thereby assuring a very light and easy operation.

The pressure fluid acts in known manner on the piston of a pressure fluid cylinder which piston, or which cylinder, is connected to the iron, to move same downward onto the work against the action of a spring or other return force. In applying the invention to an existing foot operated pressing or ironing machine, said piston or said cylinder may be connected to the pedal of the machine, thereby affording the possibility to operate the machine by foot after releasing the Bowden wire or after rendering same inoperative by loosening the mantle thereof.

Further objects and characteristic features of the invention may appear from the following description in which a constructional embodiment of my improved pressing and ironing machine is described with reference to the accompanying drawings.

Fig. 1 shows a diagrammatic elevational view of an existing pressing and ironing machine to which the invention is applied.

Fig. 2 shows on an enlarged scale a front elevational view partially in section of the pressing iron.

Fig. 3, also on an enlarged scale, shows a longitudinal sectional view of the iron proper together with the pressing plate.

Fig. 4 shows on an enlarged scale a longitudinal section through the valve means for controlling the supply and discharge of the pressure fluid.

The machine shown in the drawings consists of a pressing bed 1 mounted on a support and carrying a column 2 in which a shaft 3 is rotatably and vertically slidably mounted, such shaft being connected on the one hand through a universal joint 4 to the pedal 5, which in this case, however, does not serve as such and on the other hand carries a roller-guide 6 for a rod 7 which at one end carries the pressing iron 8, all in such a manner that the iron is adapted to be vertically moved up and down and at the same time to be displaced in a horizontal plane by means of the grip 9, by sliding the rod 7 in the guide 6 and swinging such guide about the centre-line of the shaft 3. A spring 10 operates to normally hold the pedal 5 in its upper position in which the iron is free from the pressing plate 11 lying therebeneath.

To the iron 8 there is pivoted at 12, a handle 13, of which one end, carrying a control button 14, extends to a point adjacent the grip 9 of the

iron, whilst the other end through a spring 15 engages a plunger 16 (Fig. 2) slidably arranged within a small cylinder 17 mounted within the iron and having a port 18 normally closed by said plunger, such passage opening into a U-shaped chamber 19 (Fig. 3) of which one shank is connected to a steam supply conduit 20 and the other or lower shank is connected to a steam discharge conduit 21.

The cylinder 17 is provided at some distance from the bottom, with two or more transverse ports 22 opening into an annular passage 23, which through a conduit 24 communicates with the space 25, from which a plurality of narrow passages 26 lead to the lower or working face 15 of the iron.

The pressing plate 11 (Fig. 3) is also provided with a space 28 communicating through a plurality of narrow passages 27 with the upper face of said plate, such space 28 having connected thereto a vacuum conduit 29.

The construction of the machine so far described is the usual. According to the present invention the handle 13 is provided with a second arm 30 having a lateral projection, engaging a stirrup 31 to which one end of the core 32 of a Bowden wire is connected, the mantle 33 of which at this end is inserted into an axial bore of a screw 34, threaded into a sleeve 35 surrounding said core portion 32 and being connected to a bracket 36 carrying the pivot 12 of said handle 13.

The opposite end of the mantle 33 of the Bowden wire is anchored in a corresponding manner within stationary sleeve 37 (Fig. 4), the associated end of the core 32 being connected to one arm of a bell crank lever 38 pivotably mounted at 39 on a lug projecting from a valve casing 40 secured to the bottom of the bed 1 by a support 42.

The other arm of the bell crank lever 38 is acted upon by a tension spring 41 which on the other hand is adjustably anchored to the stationary bracket 42 carrying the valve casing.

In this latter there is arranged a main valve 43 for controlling the pressure fluid which enters the valve carrying through the conduit 44, the valve 43 being loaded by the pressure fluid in the sense of closing such valve on a seat 45 within the valve casing. The main valve 43 has connected thereto through a rod 43a an auxiliary valve 46 having an annular groove 46a so that such auxiliary valve, when the main valve is closed, is moved away from its seat 47, thereby opening an outlet 48 to the atmosphere, which outlet communicates with the annular groove 46a and is closed when the main valve is moved to open position. This double acting valve 43-46 is acted upon by a valve lifter 49 against which the vertical arm of the bell crank lever 38 is held under the tension of the spring 41, which is so adjusted that normally the pressure of the bell crank lever on the valve lifter 49 is just overcome by the fluid pressure on the main valve 43, so that such valve 43 is normally closed and the auxiliary valve 46 is normally open.

Between the valve seats 45 and 47 a pressure fluid conduit 50 leads from the valve casing 40 to a second valve casing 51 (Fig. 1) containing a spring loaded non-return valve 52 and also provided with a bleeder tap 53 opening into the atmosphere. A second conduit 54 leads from the valve casing 51 to a pressure fluid cylinder 55, said conduits 50 and 54 being connected by a bypass 56 bridging said non-return valve and con-

taining a stop valve 57. The pressure fluid cylinder 55 is suspended from the bed 1 of the machine, whilst the associated piston 58 is pivotably connected to the pedal 5.

Upstream of the cylinder 55, a conduit 59 is branched off from conduit 54 such branch conduit being connected through a similar valve casing 60, comprising a non-return valve, a bleeder tap and a closable by-pass, to a second pressure fluid cylinder 61, the piston 62 of which through a lever 63 operates a vacuum control valve 64 arranged in the vacuum conduit 29 of the pressing plate 11 (Fig. 3).

The outer portion 65 of the pedal 5 is preferably hinged and folded back so as to avoid interference with the mechanical operation of the press.

The operation of the machine above described is as follows:

After the pressing iron 8, by means of the grip 9 is placed over the required portion of the work, lying on the pressing plate 11, the operator with the same hand pushes the button 14 towards the grip 9, whereby through the handle 13, 30 a tension force is exerted on the core 32 of the Bowden wire, which force, although relatively small, is sufficient to move the main valve 43 from its seat 45 against the pressure of the fluid, since it only needs to overcome the difference between the fluid pressure on the main valve 43 and the pressure of the lever 38 on the valve lifter 49 under the action of the spring 41.

Simultaneously with the opening of the valve 43, the valve 46 is closed so that the pressure fluid entering through the valve 43, assuming the stop valve 57 to be opened, flows directly into the cylinder 55, and through the medium of the piston 58, pedal 5, shaft 3, guide 6 and rod 7, draws the iron 8 with great force and abruptly onto the work, to effect local pressing thereof.

Simultaneously with the operation of the handle 13 for supplying the pressure fluid, steam is fed in the usual manner through the passages 26 into the work, in that the plunger 16 (Fig. 2) frees the inlet port 18 and the steam passes from the chamber 19 through 18, 22, 23 and 24 into chamber 25 and thence through passages 26 into the work. Through the branch conduit 59 the pressure fluid is also admitted to the cylinder 62 so that the vacuum control valve 64 is opened and the steam supplied to the work is withdrawn from the work by suction.

In the above described case (stop-valve 57 opened) the pressure on the iron 8 is maintained, so long as the button 14 is held in operating position. Upon release of the button 14 the valve 43 returns to its seat and the valve 46 opens, so that the pressure fluid by the action of the spring 41 on the piston 58, is forced from the cylinder 55 through the conduits 54, 56 and 50 and the outlet 48, thereby releasing the iron which may then be displaced for a further pressing operation.

When using the valve 52, that is to say when operating with closed stop valve 57, the release of the iron 8, after the release of the button 14, is retarded, since in that case the pressure fluid does not escape through the outlet 48, but through the tap 53 which is adjusted so as to produce a certain throttling effect. The button 14 therefore may be released after a short time (sufficient for steaming the work).

So long as the iron is held down by the pressure fluid, on the work, the evacuation of the steam through the passages 27, will of course have little or no effect. It is therefore desirable that such

evacuation will continue for some time after the valve 43 is closed. To this end serve the second non-return valve casing 60 and associated parts, of which the operation after what is said above will be clear. The respecting by-pass should then of course be closed.

In order to convert the machine from mechanical operation to foot operation, it is only necessary to turn down the hinged portion 65 of the pedal into the position shown and to operate the screw 34 (Fig. 2) so that the mantle 33 of the Bowden wire is no longer held fast so that the operation of the handle 13 for steaming the work has no effect on the supply of the pressure fluid, as the valve 43 remains shut.

It will be apparent that the machine described is very easy to operate and nevertheless produces a heavy and efficient pressing pressure. It may of course also be exclusively automatical, that is to say the piston of the pressure fluid cylinder may be directly connected to the shaft 3 or through a lever system for amplifying the pressing force. Instead of the cylinder 55 the piston 58 may be stationary and the cylinder movable, in which case this cylinder transmits the pressing force.

What I claim is:

1. A pressing machine having a movable pressing member having a grip comprising in combination: a pressure cylinder; a piston slidably arranged in said cylinder and connected to the pressing member for applying a vertical force on the pressing member; means for exerting a return force on said piston; a first valve controlling the admission of a pressure fluid to said cylinder; a second valve leading to the atmosphere and connected to said first valve so as to open when said first valve is closed and vice versa; a non-return valve having a casing and being arranged between said first valve and said cylinder; a tap in said casing leading to the atmosphere; a closable by-pass bridging said non-return valve; and a member mounted on the pressing member in the vicinity of the grip, said member controlling said valves.

2. A pressing machine having a movable pressing member having a grip comprising in combination: a pressure cylinder; a piston slidably arranged in said cylinder and connected to the pressing member for applying a vertical force on the pressing member; means for exerting a return force on said piston; a valve casing, containing a first valve controlling the admission of a pressure fluid to said cylinder and a second valve leading to the atmosphere and connected to said first valve so as to open when said first valve is closed and vice versa; a non-return valve having a casing and being arranged between said first valve and said cylinder; a tap in said casing leading to the atmosphere; a closable by-pass bridging said non-return valve; and a movable member movably mounted on the pressing member in the vicinity of the grip; a Bowden wire having one end connected to said member; a two-armed lever pivotally mounted on the casing of said first and second valve and having one arm thereof connected to the other end of said Bowden wire and another arm thereof connected to said valves; and a spring acting on said other arm of said lever in a sense of opening said first valve and closing said second valve.

3. A pressing machine having a movable pressing member having a grip comprising in combination: a pressure cylinder; a piston slidably arranged in said cylinder and connected to the

pressing member for applying a vertical force on the pressing member; means for exerting a return force on said piston; a valve casing containing a first valve controlling the admission of a pressure fluid to said cylinder and a second valve leading to the atmosphere and connected to said first valve so as to open when said first valve is closed and vice versa; a non-return valve having a casing and being arranged between said first valve and said cylinder; a tap in said casing leading to the atmosphere; a closable by-pass bridging said non-return valve; a fluid supply conduit connecting said first valve with said cylinder; a branch conduit having one end connected to said supply conduit; a second pressure cylinder arranged at the other end of said branch conduit; a non-return valve arranged in said branch conduit; a closable by-pass bridging said non-return valve; a second piston slidably arranged in said second cylinder; a control valve actuated by said second piston; means for admitting steam to the work to be pressed and means for withdrawing steam from such work; said withdrawing means being controlled by said control valve; and a member movably mounted on the pressing member in the vicinity of the grip, said member controlling said first and second valves and said steam admitting means.

4. A pressing machine having a movable pressing member having a grip comprising in combination: a pressure cylinder; a piston slidably arranged in said cylinder and connected to the pressing member for applying a vertical force on the pressing member; means for exerting a return force on said piston; a valve casing containing a first valve controlling the admission of a pressure fluid to said cylinder and a second valve leading to the atmosphere and connected to said first valve so as to open when said first valve is closed and vice versa; a non-return valve having a casing and being arranged between said first valve and said cylinder; a tap in said casing leading to the atmosphere; a closable by-pass bridging said non-return valve; a fluid supply conduit connecting said first valve with said cylinder; a branch conduit having one end connected to said supply conduit; a second pressure cylinder arranged at the other end of said branch conduit; a non-return valve arranged in said branch conduit; a closable by-pass bridging said non-return valve; a second piston slidably arranged in said second cylinder; a control valve actuated by said second piston; means for admitting steam to the work to be pressed; means for withdrawing steam from such work; said withdrawing means being controlled by said control valve; a second non-return valve having a casing and being arranged in said supply conduit between said first valve and said cylinder; a tap in said casing leading to the atmosphere; a second closable by-pass bridging said second non-return valve; and a member movably mounted on the pressing member in the vicinity of the grip, said member controlling said first and second valves and said steam admitting means.

5. A pressing machine having a movable pressing member having a grip comprising in combination: a pressure cylinder; a piston slidably arranged in said cylinder and connected to the pressing member for applying a vertical force on the pressing member; means for exerting a return force on said piston; valve casing containing a first valve controlling the admission of a pressure fluid to said cylinder; a second valve leading to the atmosphere and connected to said

first valve so as to open when said first valve is closed and vice versa; a non-return valve having a casing and being arranged between said first valve and said cylinder; a tap in said casing leading to the atmosphere; a closable bypass bridging said non-return valve; a fluid supply conduit connecting said first valve with said cylinder; a branch conduit having one end connected to said supply conduit; a second pressure cylinder arranged at the other end of said branch conduit; a non-return valve arranged in said branch conduit; a closable bypass bridging said non-return valve; a second piston slidably arranged in said second cylinder; a control valve actuated by said second piston; means for admitting steam to the work to be pressed and means for withdrawing steam from such work; said withdrawing means being controlled by said control valve; a second non-return valve having a casing and being arranged in said supply conduit between said first valve and said cylinder; a tap in said casing leading to the atmosphere; a second closable bypass bridging said second non-return valve; a member movably mounted on the pressing member in the vicinity of the grip and having an arm controlling said steam ad-

5
